BICYCLE REFLECTOR

Richard A. Disbrow, 410 Arcadia Blvd.,
Battle Creek, Mich. 49017

Filed June 13, 1975, Ser. No. 586,815

Term of patent 14 years

Int. Cl. D10—06

U.S. Cl. D10—111

FIG. 1 is a perspective view of a bicycle reflector according to my new design;

FIG. 2 is a front elevation view of the reflector of FIG. 1 on an enlarged scale;

FIG. 3 is a rear elevation view of the reflector of FIG. 1 on an enlarged scale;

FIG. 4 is a top view of the reflector of FIG. 1 on an enlarged scale;

FIG. 5 is a bottom view of the reflector of FIG. 1 on an enlarged scale;

FIG. 6 is a left side elevation view of the reflector of FIG. 1 on an enlarged scale;

FIG. 7 is a perspective view of a modification of a bicycle reflector according to my new design;

FIG. 8 is a front elevation view of the reflector of FIG. 7 on an enlarged scale;

FIG. 9 is a rear elevation view of the reflector of FIG. 7 on an enlarged scale;

FIG. 10 is a top view of the reflector of FIG. 7 on an enlarged scale;

FIG. 11 is a bottom view of the reflector of FIG. 7 on an enlarged scale;

FIG. 12 is a left side elevation view of the reflector of FIG. 7 on an enlarged scale;

FIG. 13 is a perspective view of another modification of a bicycle reflector according to my new design;

FIG. 14 is a front elevation view of the reflector of FIG. 13 on an enlarged scale;

FIG. 15 is a rear elevation view of the reflector of FIG. 13 on an enlarged scale;

FIG. 16 is a top view of the reflector of FIG. 13 on an enlarged scale;

FIG. 17 is a bottom view of the reflector of FIG. 13 on an enlarged scale; and

FIG. 18 is a left side elevation view of the reflector of FIG. 13 on an enlarged scale.

The bicycle is shown in broken lines in FIGS. 1, 7 and 13 for illustrative purposes only.

I claim:

The ornamental design for a bicycle reflector, substantially as shown and described.
